Inventor,

John H. Laskey.

UNITED STATES PATENT OFFICE.

JOHN H. LASKEY, OF BOSTON, MASSACHUSETTS, ASSIGNOR OF ONE-HALF
TO ISAAC F. DOBSON, OF SAME PLACE.

SELF-LEVELING BERTH.

SPECIFICATION forming part of Letters Patent No. 270,084, dated January 2, 1883.

Application filed May 8, 1882. (No model.)

To all whom it may concern:

Be it known that I, JOHN H. LASKEY, a citizen of the United States, residing at Boston, Massachusetts, have invented certain new and useful Improvements in Self-Leveling Berths; and I do hereby declare that the same are fully described in the following specification and illustrated in the accompanying drawings.

The primary object of this invention is to 10 so suspend the frame and the berths pendent therefrom as to reduce their oscillation to a minimum, and thereby to utilize to the utmost the space in the state-room, while giving to the occupants of the berths more room than has been 15 possible hitherto. Strain upon the bearings which support the frame is materially lessened and access to the upper berth is facilitated by my improvements.

My invention consists in an oscillating frame 20 having two or more independent berths trunnioned at their ends upon it, said frame being itself trunnioned laterally at points each side of the upper berth, and in the same horizontal plane.

It also consists in said frame and berths so suspended, in combination with a horizontal supporting-bar extending from end to end of the room in front of the upper berth, so as to give support to the frame and facilitate entering said berth.

It also consists in the devices for limiting the extent of oscillation of said frame and berths, respectively, set forth in the appended claims.

In the drawings, Figure 1 is a front view, partly in vertical section, of apparatus embodying my invention. Fig. 2 is a transverse section thereof at *xx*. Fig. 3 illustrates the springs which act upon the berths and frame, 40 and Fig. 4 is a detail of a locking device for the frame.

In my Patent No. 249,247, granted November 8, 1881, I described a berth-supporting frame suspended from double bearings at the 45 top of the state-room, with the berths midway and at the bottom of the frame. That arrangement, while entirely practical and efficient, caused a somewhat severe strain upon said bearings, since they were placed so far above 50 the berths which they served to support. It

also required more space than my present plan for the oscillation of the frame, since its movement was in a longer arc. Said bearings, being overhead, would also, in some cases, interfere with the movements of the occupant of the upper berth and reduce the space at his disposal. My present invention remedies all these difficulties. The bearings upon which the frame A swings are midway of its length and placed in the same plane horizontally as 60 the upper berth, B—one in front of and one behind said berth. The rear journal, D, may be supported by the wall or partition behind the frame, or by a suitable bar or upright; but in order to give free access to both berths without interfering with the space in either, the front journal, E, of the frame, has its bearing in a horizontal bar, F, extending across in close proximity to the front of berth B. The frame therefore oscillates on bearings about opposite to the center of the upper berth, so that said berth has no bodily movement toward and from the end of the room, and the lower berth, C, has but a slight endwise movement, because of the short radius on which it swings, 70 with the bearings of the frame so low down. Neither berth swings out into the room at all, because the bearings D E do not permit of any movement to the frame in that direction, but merely allow motion in a plane parallel to 75 the rear wall.

The shortening of the radius due to the lowering of the bearings obviously reduces the strain and wear upon them materially; and since this strain and wear is reversed with 85 every roll of the ship and continued with more or less force during the entire voyage, the practical diminution of it becomes highly important.

Considering the limited space allowed to 90 passengers on steamships, the saving in endwise play of the berth-frame is perhaps of equal importance, since berths of about the usual length can on my plan be employed in such state-rooms as are ordinarily provided, and 95 swing freely therein.

To economize space without sacrificing strength, I prefer to make the ends of the frame of angle-iron stiffened by oblique braces G', which support centrally suitable blocks for the 100

trunnions I of the two berths B and C to turn in. The ends are beveled or curved inwardly above and below the bar F, so as not to strike the walls when the frame oscillates. The top and bottom of the frame are likewise cut away for a similar reason.

The canopy K over the upper berth is not necessary, and may with its end supports be dispensed with, if desired. It serves, however, to hide the ceiling, which is continually moving with relation to the berth, and to support curtains which inclose the space between it and the berth. Hence I retain it for privacy and to conceal the movements due to the rolling and pitching of the vessel.

I partially hide from view the extremities of the frame by what may be called a "vertical stationary border," corresponding to the mat which often surrounds a framed picture, concealing the margins thereof and giving a more finished appearance to the room. This is indicated in Fig. 1 by dotted lines.

The top of the cross-bar F, I turn back horizontally as a shelf, so as to cover the central part or the whole of the upper edge of the frame A. With this construction one may climb into or out of the upper berth with much more comfort than over the separate and movable parts.

For convenience of storing baggage, &c., I provide one or more drawers, L, beneath the lower berth or under the bottom of the frame.

I limit the movement of the berths with relation to the ends of the frame by the device illustrated in Fig. 3. A curved and slotted tube, M, secured to the end of the frame A incloses two coiled springs, N N, between which, in said slot, works a vibrating finger, O, projecting upward from the end of the berth. When the vessel rolls the swinging of the berth on its trunnions causes the finger O to compress one of the springs N N, thus limiting the relative movement of berth and frame. The oscillation of the frame on its bearings is also limited by swinging plungers compressing springs inclosed in straight tubes hinged to the floor, as is indicated in Fig. 1.

When for any reason it is desired to prevent the free swinging of the berth on its trunnions, the finger O is locked to the end frame or the tube M in any convenient manner. The means illustrated in Fig. 3 consist of a vertically-sliding bolt, Q, which enters a notch in the curved tube, and is held by a staple on the finger O entering a slot in the lower hinged part of the sliding bolt. A padlock may be employed to secure it in position.

To hold the berth-frame rigidly against oscillation on its journals D E, a hinged hasp, R, is provided with a projecting bolt penetrating through the supporting-bar F into the side of the frame A, and locked in such position.

I claim as my invention—

1. An oscillating frame having two independent berths trunnioned at their ends upon it, and being itself trunnioned laterally at each side of and at the same height with the upper berth, for the purposes set forth.
2. An oscillating frame having two berths independently pivoted at their ends upon it, said frame being trunnioned laterally, as described, with its front bearing in a horizontal bar extending across the front at the height of the upper berth, for the purpose set forth.
3. The oscillating berth-frame trunnioned in lateral bearings, and the berths B C, suspended from their ends thereon, in combination with the finger O, secured to each berth, and the springs N N and slotted tube M, secured to the berth-frame, for the purpose set forth.
4. The berth-supporting frame swinging on lateral bearings, in combination with a plunger loosely connected to the bottom thereof, and a spring upon which said plunger acts, inclosed in a tube pivoted to the floor, for the purpose set forth.

85
In testimony whereof I hereto affix my signature in presence of two witnesses.

JOHN H. LASKEY.
